Patented Feb. 5, 1918.

UNITED STATES PATENT OFFICE.

FRANK R. FAGEOL, OF OAKLAND, CALIFORNIA.

NAME-PLATE CONSTRUCTION FOR MOTOR-VEHICLES.

1,255,521.

Specification of Letters Patent. Patented Feb. 5, 1918.

Application filed June 20, 1917. Serial No. 175,769.

To all whom it may concern:

Be it known that I, FRANK R. FAGEOL, a citizen of the United States, residing at Oakland, in the county of Alameda and State of California, have invented certain new and useful Improvements in Name-Plate Constructions for Motor-Vehicles, of which the following is a specification.

The present invention relates to improvements in motor vehicles and more particularly to the radiator construction or shroud thereof, and which carries the usual vehicle name plate.

The invention has for its principal objects to improve the appearance of the vehicle radiator and name plate and to provide a construction capable of illumination at night in order that the name or make of the vehicle may be easily seen. To provide a construction incorporated with the vehicle shroud and adapted to conceal the name plate illuminating means, whereby the artistic appearance of the name plate is not detracted from in the day.

The invention consists broadly in a radiator shroud provided in its upper portion with a compartment opening toward the front of the vehicle and for containing an illuminating means, the opening in said compartment being covered by a suitable transparent or semi-transparent name plate.

With the above mentioned and other objects in view, the invention consists in the novel construction and combination of parts hereinafter described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

To more fully comprehend the invention reference is directed to the accompanying drawings, wherein—

Figure 1 is a view in plan of the preferred embodiment of my invention.

Fig. 2 is a detail sectional view taken on the line 2—2 of Fig. 1.

Fig. 3 is a sectional view taken on line 3—3 of Fig. 2, viewed in the direction of the arrows.

Referring more particularly to the several views of the drawings, wherein like characters of reference designate corresponding

parts, 1 indicates a suitable vehicle radiator, the side walls of which are surrounded by a suitable shroud 2, open at its front and rear, and preferably formed of cast metal; 60 the radiator being removably mounted therein in any well known manner. The shroud is provided with the usual radiator filling opening 3 which communicates with the radiator at its top in any suitable manner. 65

Preferably cast within the upper portion of said shroud is a suitable compartment or chamber 4 closed by the surrounding side and end walls 5, and opening, as at 6, 70 through the shroud front wall 7. The compartment or chamber 5 and opening 6 thereof may be of any suitable shape, dependent upon the type of illuminating means employed or configuration of the name plate 75 used. The opening 6 is adapted to be closed by a removable transparent or semi-transparent vehicle name plate 8 which carries the vehicle name.

The name plate 8 is retained in position 80 over the opening by a suitable open frame 9 within the rear of which said name plate is received, the frame being detachably secured in position in any suitable manner, as by screws 10. One end wall of the compartment or chamber 4 is provided with an opening 11 through which is adapted to extend a suitable illuminating means 12 preferably in the form of an electric lamp, said lamp being supplied with current 90 through leads 13 extending to any suitable point.

It will be apparent that I have provided a radiator construction of an improved type, 95 wherein the vehicle name plate is capable of being illuminated at night and have constructed an illuminating means and positioned the same in such manner as not to detract from the appearance of the shroud, but on the other hand it may be said that 100 an ornamental appearance is added to the shroud construction around the name plate.

Having thus described my invention what I claim as new and desire to protect by Letters Patent is:

A vehicle radiator shroud of cast metal provided in its upper portion with an elongated integral compartment or chamber closed at its side and end walls by portions of said shroud and having an opening 110 through the front wall thereof, a transparent plate positioned over the opening in the

front wall of said shroud for closing said compartment or chamber, an open elongated frame engaging the edges of said plate, and means for clamping the said plate to the 5 radiator shroud surrounding the said opening to retain said transparent plate in position over said opening.

In testimony whereof I have signed my name to this specification in the presence of one subscribing witness.

FRANK R. FAGEOL.

Witness:

HARRY A. TOTTEN.
